UNITED STATES PATENT OFFICE.

KENNETH MCLEOD, OF SAN FRANCISCO, CALIFORNIA.

SECTIONAL CONCRETE-FORM.

1,322,034.

Specification of Letters Patent. Patented Nov. 18, 1919.

Application filed August 22, 1918. Serial No. 251,703.

To all whom it may concern:

Be it known that I, KENNETH MCLEOD, a citizen of the United States, residing in the city and county of San Francisco, State of California, have invented a new and useful Improvement in Sectional Concrete-Forms, of which the following is a specification.

My invention relates to improvements in sectional concrete forms wherein a movable framework operates in conjunction with a series of sections shaped to form the hull of a ship or the like when moved into connection with each other; and the objects 15 of my invention are

First, to provide an improved construction for sectional concrete forms;

Second, to provide an improved construction of the character described wherein the 20 sections are permanent and may be easily and readily moved into and out of connection with each other and to be reused on subsequent similar concrete structures.

The invention consists in the particular 25 details of construction as set forth in the accompanying drawings and described in the specifications and claims forming a part hereof, and in which—

Figure 1 is a broken plan view of one 30 half of a formed structure and one half of my improved form;

Fig. 2 is a broken side elevation of Fig. 1;

Fig. 3 is a transverse sectional view on an enlarged scale taken on line 3—3 of Fig. 35 1 in the direction indicated;

Fig. 4 is a horizontal sectional view, on an enlarged scale, taken on line 4—4 of Fig. 3 of the drawings in the direction indicated;

Fig. 5 is a modified form of the construction disclosed in Fig. 4;

Fig. 6 is a transverse sectional view taken on line 6—6 of Fig. 1 in the direction indicated and on an enlarged scale;

Fig. 7 is a similar view taken on line 7—7 45 of Fig. 1; and

Fig. 8 is a broken detail view disclosing the manner in which adjacent edges of the form section are rigidly secured together.

Referring to the drawings the numeral 1 50 is used to designate in general a mold or form for concrete ships and the like comprising a series of sections 2 shaped to form a hull of a ship or the like when connected together.

Each section 2 is supported by a suitable

framework 3 consisting of the usual network of vertically and horizontally disposed beams of any suitable type, as disclosed in Figs. 3, 6 and 7 of the drawings.

Wheels 4 are rotatably mounted upon 60 each framework 3 supporting the sections 2 whereby said framework 3 and sections 2 thereon may be easily and readily moved into connection with each other and retired from the completed concrete structure without destroying said framework or the sections thereon.

The frames 3 and the sections 2 thereon are raised and supported in an operative position by means of suitable wedges 6 which 70 are placed under the lower surfaces or edges of the said frames 3 whereby the sections 2 may be dropped or released from a completed concrete structure in a manner hereinafter more fully set forth.

The edges 7 of each section 2 at the junction with another section are beveled as disclosed in detail in Fig. 8 of the drawings and said sections 2 are provided near their edges, in one form of the invention, with battens 8 which may be tightly and rigidly drawn together to insure a rigid and substantially leak proof joint by means of suitable bolts 9 or the like. Or as disclosed in detail in Fig. 8 of the drawings the battens 80 8 may be secured near certain edges only of said sections 2, portions of the frames 3 being secured near the remaining edges of said sections. In this case the battens 8 are drawn toward the frame members 3 by 85 means of the bolts 9 as previously described.

The interior portion of the form may be built up in any manner whereby a suitable channel or mold is formed between the sections 2 and said interior portion of the structure or form.

I prefer to use the form of construction disclosed in Figs. 4 and 5 of the drawings wherein a series of interior U-shaped sections 12 are provided with lateral extensions 14 on one leg or flange thereof, said lateral extension 14 operating in conjunction with the legs of adjacent sections to form ribs 15 in the completed concrete structure.

The U-shaped sections 12 are mounted 105 upon frames 16 which are detachably mounted upon stringers 17.

The sections 12 may be provided with telescoping joints 18 as disclosed in Fig. 5 of the drawings by means of which the de- 110

sign of the structure may be altered to increase the distance between the ribs 15 or the entire length of the ship to be poured.

The form or mold as represented by the 5 space between the sections 2 and 12 is maintained by means of concrete separators 19 which also serve as a support for the interior structure or sections 12. The separators 19 are first laid upon the interior bottom of the 10 sections 2 to support sections 12 and as the pouring of the concrete progresses new separators 19 are added to maintain the channel between the outer and inner sections 2 and 12 respectively, as disclosed in Figs. 3, 6 and 7 15 of the drawings. These separators 19 may be held in position by wiring to the forms or in any other suitable manner.

In setting up the form the sections 2, by means of the wheeled frames 3, are moved 20 into juxtaposition with the site upon which the ship is to be poured and by means of the wedges 6 said frames 3 and the sections 2 thereon are raised to what I term an operative position.

25 The separators 19 are then laid upon the interior bottom of the sections 2 and the sections 12 are then built up and connected upon said separators 19.

After the concrete structure has set the 30 sections 2 may be easily and readily removed by releasing and removing the outer or farthest wedges 6, that is, the wedges farthest from the ship, leaving only a single line of inner wedges 6 supporting the 35 frames 3 and sections 2 thereon. This will cause the upper portion or end of the sections 2 and their supporting frames 3 to retire or move outwardly and away from the finished concrete structure so that any overhanging portions cast upon the exterior surface of the said finished structure will be 40 liberated from the mold or section by such outward movement.

The remaining or inward line of wedges 45 is then removed which will lower the entire frame 3 to the ground and resting upon the wheels 4 which support it. The frames can then be moved away from the structure as disclosed in dotted lines in Fig. 3 of the 50 drawings to be used for subsequent structures of similar nature.

Having thus described my invention what I claim as new and desire to secure by Letters Patent is—

55 1. A form for concrete ships and the like comprising a series of sections having beveled junctional edges; wheels mounted to support the sections rigidly so that they may be moved into conjunction with each 60 other to form a mold for a concrete structure, and separated from each other to release a finished structure without destroying said sections; and means for detachably securing the beveled edges of adjacent sections rigidly together.

2. A form for concrete ships and the like comprising a series of sections having beveled junctional edges; a suitable framework supporting the sections; wheels mounted upon the framework adapted to support the 70 same and the sections rigidly so that they may be moved into conjunction with each other to form a mold and moved away from a completed structure formed within the mold without destroying said sections; and 75 means for detachably securing the beveled edges of the adjacent sections rigidly together.

3. A form for concrete ships and the like comprising a series of sections having beveled junctional edges; a suitable framework supporting the sections; wheels mounted upon the framework and adapted to support the same and the sections rigidly so that they may be moved into conjunction with 80 each other to form a mold and moved away from a completed structure formed within the mold without destroying said sections; means for detachably securing the beveled edges of adjacent sections rigidly together; 85 and means for raising the wheels, framework and sections and retaining them in position to form a mold.

4. A form for concrete ships and the like comprising a series of sections having beveled junctional edges; a suitable framework supporting the sections; wheels mounted upon the framework and adapted to support the same and the sections rigidly so that they may be moved into conjunction with each 95 other to form a mold and moved away from a completed structure formed within the mold without destroying said sections; means for detachably securing the beveled edges of adjacent sections rigidly together; and suitable wedges arranged to raise the sections and wheels thereon from the ground to rigidly support the frames and sections in operative position.

5. A form for concrete ships and the like 110 comprising a series of detachable sections having beveled junctional edges, said several sections being shaped to form the hull of a ship or the like when moved into conjunction with and connected to each other; a 115 suitable frame work for each section; wheels mounted upon each framework for rigidly supporting said sections while they are moved into and out of position; and means for detachably securing the adjacent beveled edges of adjacent sections rigidly together.

6. A form for concrete ships and the like comprising a series of detachable sections having beveled junctional edges, said several sections being shaped to form the hull of a 125 ship or the like when moved into conjunction with and connected to each other; a suitable frame work for each section; wheels mounted upon each framework for rigidly supporting said sections while they are moved 130

into and out of position; means for detachably securing the adjacent beveled edges of adjacent sections rigidly together; and means for raising the frames and sections 5 thereon into operative position whereby said frames and sections may be retired from a completed structure when said raising means are removed.

7. A form for concrete ships and the like 10 comprising a series of detachable sections having beveled junctional edges, said several sections being shaped to form the hull of a ship or the like when moved into conjunction with and connected to each other; a 15 suitable frame work for each section; wheels mounted upon each framework for rigidly supporting said sections while they are moved into and out of position; means for detachably securing the adjacent beveled 20 edges of adjacent sections rigidly together; and suitable wedges arranged to raise the frames and sections thereon into an operative position whereby said frames and sections may be easily removed from a com-

pleted concrete structure without damage by 25 releasing and removing the wedges.

8. A form for concrete ships and the like comprising a series of sections having beveled edges, said sections being severally shaped to form the hull of a ship when 30 moved into conjunction with each other and connected together; suitable battens secured near the edges of each section; means for moving the battens toward each other whereby the beveled edges may be closely and rigidly held together; a suitable frame work for supporting each section; wheels mounted upon each section whereby the frames and sections thereon may be easily moved into conjunction with each other and retired from 35 a completed concrete structure; and suitable wedges arranged to raise the frames and sections thereon into operative position whereby said frames and sections may be easily removed by removing said wedges. 40

In witness whereof I hereunto set my signature.

KENNETH McLEOD.
